UNITED STATES PATENT OFFICE

FREDERICK M. VENZIE, OF PHILADELPHIA, PENNSYLVANIA

BUILDING STRUCTURE

Application filed May 17, 1929. Serial No. 363,893.

This invention, generally stated, relates to a building structure and has more particular relation to a block of cementitious material as used in a ceiling construction.

5 The leading object of the present invention is to provide a ceiling block of cementitious material which not only provides fireproofing proclivities but also serves to prevent unnecessary and vibratory noises.

10 A further object of the present invention is to provide a block or slab of the character stated for ceiling construction in which the reinforcing rods and the members employed for suspending the block or slab are so spaced 15 with respect to one another that they do not come into bodily contact.

A still further object of the present invention is to provide a novel form of block or slab suspension in which the hooks employed 20 for suspending the block or slab are in no way connected with the longitudinal reinforcing rods.

25 Other and further objects of the present invention reside in the provision of general details of construction and in the arrangement and combination and connection of parts for attaining the results sought by the foregoing objects.

The invention consists of the novel construction hereinafter described and finally claimed.

30 The nature, characteristic features and scope of the invention will be more fully understood from the following description 35 taken in connection with the accompanying drawings forming part hereof, and in which:

Fig. 1, is a top or plan view of a block or slab embodying the invention.

Fig. 2, is a view in longitudinal section 40 taken upon the line 2—2 of Fig. 1.

Fig. 3, is a view in elevation looking at the left hand side of Fig. 2.

Fig. 4, is a view in elevation looking at the right hand side of Fig. 2.

Fig. 5, is a fragmentary view illustrating 45 a block or slab as suspended from a girder.

For the purpose of illustrating my invention I have shown in the accompanying drawings one form thereof which is at present preferred by me, since the same has been found

in practice to give satisfactory and reliable results, although it is to be understood that the various instrumentalities of which my invention consists can be variously arranged and organized and that my invention is not 55 limited to the precise arrangement and organization of the instrumentalities as herein shown and described.

Referring to the drawings in detail, the reference numeral 1 designates a block or slab of cementitious material as employed in the erecting of ceilings. Each end of the block or slab is provided with cut-away portions, those at the left hand end of Fig. 1 being designated by reference numeral 2, 60 and those at the right hand end of Fig. 1 being designated by the reference numeral 3. Extended longitudinally of the block or slab 1 is a pair of spaced metallic members 4 apertured as at 5. The outer end of each of these 65 members 4 projects through a cut-away portion 2 in an upwardly inclined manner, best seen in Fig. 2. These projected ends of the members 4 provide hook-accommodating 70 members. As shown in Fig. 5, a hook 6 is used in conjunction with a girder 7 for suspending a block or slab at each end of the block. That end of the block or slab opposite the longitudinal members 4 is provided 75 with a laterally extended cross piece which is 80 embedded in the cementitious material of the block or slab as are the members 4. However, the members 4 are relatively flat, whereas the cross member 8 is preferably of circular cross section. It may also be stated that 85 the apertures of the members 4 serve to accommodate the cementitious material so as to provide a good anchorage. The cross member 8 is bent outwardly as at 9 to form hanger 90 accommodating portions which project into the cut-away portions 3 of the block or slab. Also extended laterally of the block or slab but at the end opposite the cross piece 8 is another cross piece 10 also of circular cross section 95 which serves as a reinforcement for the end of the block or slab. In the connection it is to be noted that this reinforcing piece 10 does not touch the members 4 so that no conducting of a metallic sound is present. This is also true with respect to the longitudinal 100

reinforcing pieces 11 which do not touch either the cross piece 8 or 10 or the members 4.

5 A construction of parts as above set forth provides a very simple and efficient ceiling block in which vibratory noises therethrough is reduced to a minimum due to the lack of contacting of metal parts within the block.

10 Further, the above described block is very simple in structure and comparatively easy to make, and may be readily placed in position upon a ceiling by unskilled labor.

What I claim is:

15 1. In a building construction, a slab of cementitious material of relatively thick cross section having embedded therein parallel, longitudinal reinforcing rods, each end of said block having spaced cut away portions, a pair of spaced longitudinal relatively flat 20 apertured hook accommodating members embedded in said block and projected through the cut-away portions at one end of the block, and a laterally extended hook accommodating member embedded in the block, said member having outwardly bent portions projected cross-wise and through the said spaced cut-away portions at the other end of the block.

25 2. In a building construction, a slab of cementitious material of relatively thick cross section having embedded therein parallel, longitudinal reinforcing rods, each end of said block having spaced cut away portions, a pair of spaced longitudinal relatively flat 30 apertured hook accommodating members embedded in said block and projected at an angle through the cut-away portions at one end of the block, and a laterally extended hook accommodating member embedded in 35 the block, said member having outwardly bent portions projected cross-wise and at an angle through the said spaced cut-away portions at the other end of the block.

40 3. A building element comprising a pre-cast slab having embedded therein longitudinally extended conventional reinforcing rods, each end of said slab having spaced cut-away portions arranged substantially in parallelism with said reinforcing rods, a pair of 45 relatively flat suspension hook receiving portions embedded in said slab at one end thereof and projected in an upwardly extended manner into adjacent cut-away portions, and a cross rod embedded in said slab at its other 50 end, said cross rod having bent outwardly therefrom portions which project into adjacent cut-away portions of the slab in an upwardly extended manner cross-wise of said cut-away portions to receive suspension 55 hooks.

60 4. A building element comprising a pre-cast slab having embedded therein longitudinally extended conventional reinforcing rods, each end of said slab having spaced 65 cut-away portions arranged substantially in

parallelism with said reinforcing rods, a pair of relatively flat suspension hook receiving portions embedded in said slab at one end thereof and projected in an upwardly extended manner into adjacent cut away portions, and a cross rod arranged zig-zag fashion embedded in said slab at its other end, said cross rod having bent outwardly therefrom portions which project into adjacent cut away portions of the slab in an upwardly extended manner cross-wise of said cut away portions to receive suspension hooks.

65 5. A building element comprising a pre-cast slab having embedded therein longitudinally extended conventional reinforcing rods each end of said slab having spaced cut away portions arranged substantially in parallelism with said reinforcing rods, a pair of relatively flat suspension hook receiving portions embedded in said slab at one end thereof, and projected in an upwardly extended manner into adjacent cut away portions, a cross rod embedded in said slab at its other end, said cross rod having bent outwardly therefrom portions which project into adjacent cut away portions of the slab in an upwardly extended manner cross-wise of said cut away portions to receive suspension hooks, and an auxiliary reinforcing rod arranged adjacent said longitudinally extended hook suspension members and at right angles to the conventional reinforcing rods.
